QUIN-TOP

Roger Neilson, New York, N. Y.

Application January 5, 1951, Serial No. 204,637

6 Claims. (Cl. 46—69)

1

This invention relates to a toy, and more particularly to a toy which will enable a person to simultaneously spin a plurality of revoluble tops.

The object of the invention is to provide a toy wherein a plurality of tops can be simultaneously spun upon actuation of the toy so that a plurality of spinning tops will provide a source of amusement or recreation to the user.

Another object of the invention is to provide a toy to be used for simultaneously spinning a plurality of tops which may be five in number, the toy being constructed so that upon application of a downwardly directed pressure thereon, the tops will be released and spun, the toy of the present invention adapted to be readily rewound so that it can be used over and over again.

A further object of the invention is to provide a toy which is extremely simple and inexpensive to manufacture.

Other objects and advantages will be apparent during the course of the following description.

In the accompanying drawings, forming a part of this application, and in which like numerals are used to designate like parts throughout the same.

Figure 1 is a top plan view of the toy spinning device, constructed according to the present invention.

Figure 2 is a side elevational view of the toy spinning device of the present invention.

Figure 3 is a bottom plan view of the device, with two of the rotatable tops in section to illustrate the gear arrangement.

Figure 4 is a side elevational view of the device of the present invention, with parts broken away and in section and showing the device in the "set" position.

Figure 5 is a sectional view taken on the line 5—5 of Figure 4.

Figure 6 is a view similar to Figure 4, but with the parts in the "unlocked" position.

Figure 7 is a top plan view of the base showing the ring gear and ratchet assembly.

Figure 8 is a side elevational view of the assembly of Figure 7.

Figure 9 is a view similar to Figure 8, but taken at 90° thereto.

Figure 10 is a vertical sectional view taken through the body member.

Figure 11 is a bottom plan view of the body member of Figure 10.

Figure 12 is an enlarged sectional view showing one of the sockets for receiving the shank of the top.

Figure 13 is a sectional view taken on the line 13—13 of Figure 14.

2

Figure 14 is a sectional view taken on the line 14—14 of Figure 12.

Figure 15 is a fragmentary bottom plan view showing a socket.

Figure 16 is an enlarged fragmentary sectional view showing the method of winding and unwinding the device.

Figure 17 is a top plan view of the coil spring.

Figure 18 is a vertical sectional view taken 10 through the cap.

Figure 19 is a bottom plan view of the cap.

Referring in detail to the drawings, the numeral 30 designates any one of a plurality of revoluble tops, and each of the tops 30 includes a conical bottom portion 31, Figure 2, and a circular disk portion 32 which is arranged on the upper end of the support portion 31. Extending upwardly from the center of the disk portion 32 is a vertically disposed shank 33, and a portion of the shank 33 is provided with gear teeth 34 for a purpose to be later described. Extending downwardly from the upper end of the shank 33 is a hole 35, Figure 14, and a pair of diametrically opposed slits 36 communicate with the hole 35 for a purpose to be later described.

The device of the present invention is shown in the drawings being used for simultaneously spinning five of the tops 30, but it is to be understood that a greater or less number of these tops 30 may be spun at one time if desired. In Figures 10 and 11 there is shown the body member which is indicated by the numeral 37, and the body member 37 includes a vertically disposed sleeve 38 that is provided with a longitudinally extending bore 46. Extending outwardly from the lower end of the sleeve 38 is a horizontally disposed flange 39, and the flange 39 is provided with a plurality of spaced sockets 40. A pin 41 is arranged in each of the sockets 40, the pins 41 depending from top portions 45 that are arranged over each of the sockets 40.

Arranged in the lower end of the sleeve 38 and surrounding the bore 46 is an annular recess 42. The recess 42 is shaped so as to provide ratchet teeth 43 in the sleeve 38 for a purpose to be subsequently described. The sleeve 38 is further provided with a cut-out 44, the cut-out 44 being arranged in the lower end of the sleeve 38 and having a substantially L-shape, Figure 10.

Referring to Figures 7, 8 and 9 there is shown the base 47 which forms part of this invention. The base 47 includes an annular collar 48 that is adapted to be rotatably arranged in the annular recess 42, and the upper end of the collar 48 is provided with inclined ratchet teeth 49 for engaging the ratchet teeth 43 on the sleeve 38.

Thus, the provision of these ratchet teeth enables the base to be locked against accidental rotation of the base or accidental rotation of the tops 30 with respect to body member 37. The base 47 further includes a vertically disposed stem 50 that projects through the bore 46 in the sleeve 38, and the stem 50 is provided with a slot 51 in its upper end, Figures 7 and 8. Arranged around the bottom of the collar 48 is a ring gear 52 having teeth thereon for engaging the teeth 34 on the shanks 33 of the tops 30. A lip 53 is arranged on the lower surface of the ring gear 52, and the lip 53 provides a hand grip for use in winding the toy.

In Figures 4, 6 and 16, there is shown the coil spring 54 which surrounds the stem 50 of the base 47. The coil spring 54, Figure 17, has one of its ends 55 seated in the cut-out 44 in the sleeve 38, while the other or upper end of the coil spring 54 which is designated by the numeral 56 is seated in the slot 51 in the upper end of the stem 50. The coil spring 54 can be wound by means of the lip 53, as shown in Figure 16, and then when the energy in the wound coil spring 54 is released, the ring gear 52 will be rotated to thereby rotate the tops 30 and cause these tops to be simultaneously spun and thus provide a source of recreation and amusement to the user or onlookers.

In Figures 18 and 19 there is shown a cap which is indicated by the numeral 57, and the cap 57 includes a top portion 58 and an annular portion 59 that surrounds the upper end of the stem 50. The cap 57 is further provided with a partition 60 which is adapted to be seated in the slot 51 in the upper end of the stem 50.

From the foregoing, it is apparent that a device has been provided for simultaneously spinning a plurality of tops, such as the tops 30. The tops 30 are initially arranged so that the upper ends of the shanks 33 project into the sockets 40, the pins 41 projecting into the holes 35 in the shanks 33. Then, with one hand, the user grips the body member 37 and with the other hand grips the lip 53 and rotates the base 47 against the tension of the coil spring 54. After the base 47 has been rotated the proper amount, the lip 53 can be released and the inclined ratchet teeth 43 and 49 will prevent accidental unwinding or rotation of the base 47. Then, when it is desired to release or spin the tops 30, the user merely exerts a downwardly directed pressure on the cap 57 to thereby cause the base 47 to move from the position shown in Figure 4 to the position shown in Figure 6. This frees the ratchet teeth 49 from the ratchet teeth 43 so that the coil spring 54 will rotate the base 47. As the base 47 rotates, the ring gear 52 will rotate the tops 30, since the ring gear 52 is arranged in meshing engagement with the teeth 34 on the shanks 33 of the tops. The shanks of the tops will automatically be released from the sockets 40. The various parts of the device can be made of any suitable material, and the size may be varied as desired. In winding the spring 54, the member 37 is held stationary while the base 47 is rotated.

Having described the invention, what is claimed as new is:

1. In a toy for simultaneously spinning a plurality of tops, a body member provided with a vertically disposed bore, a base having a stem projecting through said bore, a coil spring circumposed on said stem, a ring gear provided on said base, there being a plurality of spaced sockets arranged in said body member, a top positioned in each of said sockets and having gear teeth for

meshing with said gear ring, and a cap mounted on the upper end of said stem.

2. In a toy for simultaneously spinning a plurality of tops, a body member provided with a vertically disposed bore, a base having a stem projecting through said bore, a coil spring circumposed on said stem, a ring gear provided on said base, there being a plurality of spaced sockets arranged in said body member, a top positioned in each of said sockets and having gear teeth for meshing with said gear ring, a cap mounted on the upper end of said stem, and a lip arranged on the bottom of said base for winding the toy.

3. In a toy for simultaneously spinning a plurality of tops, a body member provided with a vertically disposed bore, a base having a stem projecting through said bore, a coil spring circumposed on said stem, a ring gear provided on said base, there being a plurality of spaced sockets arranged in said body member, a top positioned in each of said sockets and having gear teeth for meshing with said gear ring, a cap mounted on the upper end of said stem, a lip arranged on the bottom of said base for winding the toy, ratchet teeth in said body member concentric with said base, and ratchet teeth on said base concentric with said stem adapted to coact with the ratchet teeth in said body, for preventing accidental rotation of said base, said tops being rotatably arranged in said sockets.

4. The apparatus as described in claim 3 wherein said cap is adapted to be depressed when the tops are to be actuated.

5. In a toy for simultaneously spinning a plurality of tops, each of the tops comprising a lower conical support portion, a circular disk portion mounted on the upper end of said support portion, a vertically disposed shank extending upwardly from the center of said disk portion, a plurality of circumferentially arranged teeth on said shank, there being a hole arranged in the center of said shank and extending downwardly from the top thereof, a body member including a central vertically disposed sleeve provided with a longitudinally extending bore, a horizontally disposed flange extending from the lower edge of said sleeve and provided with a plurality of spaced sockets for receiving therein the upper ends of said shanks, a pin arranged in each of said sockets and projecting into the holes in said shanks, there being a circular recess in the bottom of said sleeve and providing ratchet teeth in said sleeve, said sleeve having a cut-out in its lower end, a base including a vertically disposed stem projecting rotatably through the bore in said body member, there being a slit in the upper end of said stem, an annular collar surrounding said stem and projecting into said recess and provided with inclined teeth for engaging said ratchet teeth, a ring gear arranged around said collar for engaging the gear teeth on the shanks of said tops, a lip positioned on said ring gear and adapted to be engaged by the user's fingers for winding the toy, and a coil spring circumposed on said stem and having its lower end positioned in the cut-out in said sleeve and its upper end position in the slit in said stem.

6. In a toy for simultaneously spinning a plurality of tops, each of the tops comprising a lower conical support portion, a circular disk portion mounted on the upper end of said support portion, a vertically disposed shank extending upwardly from the center of said disk portion, a plurality of circumferentially arranged teeth on

said shank, there being a hole arranged in the center of said shank and extending downwardly from the top thereof, a body member including a central vertically disposed sleeve provided with a longitudinally extending bore, a horizontally disposed flange extending from the lower edge of said sleeve and provided with a plurality of spaced sockets for receiving therein the upper ends of said shanks, a pin arranged in each of said sockets and projecting into the holes in 10
 said shanks, there being a circular recess in the bottom of said sleeve and providing ratchet teeth in said sleeve, said sleeve having a cut-out in its lower end, a base including a vertically disposed stem projecting rotatably through the bore in 15
 said body member, there being a slit in the upper end of said stem, an annular collar surrounding said stem and projecting into said recess and provided with inclined teeth for engaging said 20
 ratchet teeth, a ring gear arranged around said

collar for engaging the gear teeth on the shanks of said tops, a lip positioned on said ring gear and adapted to be engaged by the user's fingers for winding the toy, a coil spring circumposed on said stem and having its lower end positioned in the cut-out in said sleeve and its upper end positioned in the slit in said stem, and a cap mounted on the upper end of said stem and provided with a partition seated in the slit in said stem.
